UNITED STATES PATENT OFFICE.

WILLIAM C. BREITENBACH, OF PHILADELPHIA, PENNSYLVANIA.

DESIGN FOR A GAME OR PUZZLE BOARD.

SPECIFICATION forming part of Design No. 31,295, dated July 25, 1899.

Application filed June 19, 1899. Serial No. 721,167. Term of patent 7 years.

To all whom it may concern:

Be it known that I, WILLIAM C. BREITENBACH, a citizen of the United States, and a resident of Philadelphia, in the county of Philadelphia and State of Pennsylvania, have invented and produced a new and original Design for a Puzzle or Game Board; and I do declare the following to be a full, clear, and exact description of the invention, such as will enable others skilled in the art to which it appertains to make and use the same, reference being had to the accompanying drawings, which form a part of this specification.

Figure 1 of the drawings is a plan view of my puzzle or game board. Fig. 2 is a section on the line $x-x$, Fig. 1.

This invention has relation to a certain new and original design for a game or puzzle board; and it consists in the novel form and configuration thereof hereinafter described, and illustrated in the accompanying drawings.

The leading feature of my design consists in a game-board having thereon a rectangu-

lar field or figure, within which is a second rectangle whose angles bisect the sides of the first rectangle, with an opening at the common center from which radiate lines to each corner and to the center point of each side of the outer rectangle. At each point of intersection and meeting of the radial lines with the lines of the inner and outer rectangles is formed an opening, the entire design therefore presenting thirteen openings, one at the center and the other twelve on lines radiating from the center of the center opening and also on the sides of the two rectangles.

What I claim is—

The design for a game or puzzle board, substantially as herein shown and described.

In testimony whereof I affix my signature in presence of two witnesses.

WILLIAM C. BREITENBACH.
